UNITED STATES PATENT OFFICE.

MAURICE J. WOHL AND HARRY HERTZBERG, OF NEW YORK, N. Y.

DESIGN FOR A GLOBE FOR ARC-LAMPS.

No. 39,439.

Specification for Design.

Patented Aug. 4, 1908.

Application filed April 14, 1908. Serial No. 427,092. Term of patent 14 years.

To all whom it may concern:

Be it known that MAURICE J. WOHL and HARRY HERTZBERG, citizens of the United States, and residents, respectively, of the city of New York, borough of Manhattan, county and State of New York, and of the city of New York, borough of Brooklyn, county of Kings, and State of New York, have invented a new, original, and ornamental Design for a Globe for Arc-Lamps, of which the following is a specification, reference being had to the accompanying drawing, forming part thereof.

The figure is an elevation of a globe for an arc lamp, showing our new design.

We claim:

The ornamental design for a globe for an arc lamp as shown.

MAURICE J. WOHL.
HARRY HERTZBERG.
